A circular diagram of a dial gauge. The outer ring has markings from 0 to 100 in increments of 10. The inner ring has markings from 0 to 100 in increments of 10. Handwritten text on the diagram includes:

- Top right: "Inventor"
- Top center: "Albert H Reynolds"
- Bottom right: "P. J. Edmunds" and "Attorney"
- Left side: "Day 25 22"
- Bottom left: "26"

UNITED STATES PATENT OFFICE.

ALBERT H. REYNOLDS, OF LONDON, ONTARIO, CANADA.

AUTOMATIC MACHINE FOR LOADING AND SCREENING COAL AND OTHER MATERIAL BY POWER.

1,138,790.

Specification of Letters Patent.

Patented May 11, 1915.

Application filed November 10, 1913. Serial No. 800,240.

To all whom it may concern:

Be it known that I, ALBERT H. REYNOLDS, a subject of the King of Great Britain, and a resident of the city of London, in the 5 county of Middlesex, in the Province of Ontario, Canada, have invented an Automatic Machine for Loading and Screening Coal and Other Material by Power, of which the following is a specification.

10 My invention relates to an automatic machine for loading and screening coal and the like by power, and has as its principal object, an apparatus which may be economically constructed and which will rapidly 15 and cheaply screen materials such as coal and the like.

A further object of my invention is to provide a cheap but efficient form of elevator for use in connection with the screening apparatus.

In the accompanying drawing:—Figure 1 is a perspective view of a screening apparatus made according to my invention. Fig. 2 is a side elevation of the device shown 25 in Fig. 1, illustrating the manner in which the elevator bucket takes up material. Fig. 3 is a detail view showing the elevator bucket and its relation to conveyer chain and sprocket wheel.

30 In the separate views the same part is designated by the same reference character.

Referring more particularly to the drawing, 1 represents a frame provided with a platform 2 which is mounted on suitable 35 pairs of wheels such as 3—3. As best shown in Fig. 2, the frame 1 carries on the underside thereof a motor 4 which might be of any preferred type, either electric or otherwise, and which is preferably geared to 40 drive the wheels 3 shown at the right of Fig. 2. The motor 4 is connected also to a shaft 5 which is provided with suitable gearing, not shown, by which it guides the shaft 6, which extends transversely beneath the 45 frame 1. However, it will be understood that it is not necessary to my invention that the frame 1 be motor driven, or that the shaft 5 be driven from a motor carried by the frame. Any suitable means for rotating 50 the shaft 5 may be used.

At one end of the shaft 6 is a sprocket wheel 7 around which runs a sprocket chain 8 which drives a second wheel 9 journaled at the upper end of a pair of arms 10 which 55 form a part of a framework 11 carried at

one end of the horizontal frame 1. The wheel 9, as best shown in Fig. 1, is fixed to a transverse shaft 12 which has fixed to it in turn a sprocket wheel 13 which is centrally between the two arms 10—10. 60

Pivottally connected to the shaft 12 is a frame 14, the connection with the shaft being at the extreme upper end of the frame.

The upper ends of the frame 14 carry bushing such as 15 which extends through the arms 10 on the outside of the shaft 12 and which are fastened at their outer ends to curved levers such as 16—16 by which the position of the frame 14 can be adjusted around shaft 12 as an axis. Any suitable 65 arrangement may be used for operating the levers 16, and I have shown for this purpose a pair of cords 17—17 which pass around pulleys 18 suitably mounted on the sides of the frame 11 and thence are carried to drums 19, there being a pair of such drums, one on each side of the frame 11 which are shown as operated by a common crank or lever 20. 70

At its outer or lower end the frame 14 carries a shaft 21 on which is mounted a sprocket wheel 22 around which and the wheel 13 the conveyer chain 23 is adapted to run. The chain 23 is shown as carrying two buckets 24, although more may be used 80 if so desired. It will be noted, moreover, that the wheels 13 and 22 are set centrally with respect to their shafts and that there is only one chain for supporting and elevating the buckets. 85

As clearly shown in Fig. 3, each bucket comprises a relatively long, relatively shallow portion such as 25, the under surface of which is rigidly attached to a shoe or plate 26, the plate 26 being provided with a pair 90 of lugs 27 by which the buckets 24 are pivotally connected to the chain 23. It will be understood that the upper end of the bucket shown in Fig. 3 serves as the discharge end, while the lower end is provided with a cutter plate such as 28 which is riveted to the upstanding edges of the portion 25, and which forms a pocket at one end of the bucket in which the majority of the material will collect and be transported. It will be seen that 100 the cutter plate 28 is of a somewhat quadrilateral shape in side elevation, and it will be apparent from Fig. 2 that the bucket is adapted to dig through a pile of material either from the ground upward or from the 110

top downward until it has taken a section out of the pile. It will be seen that the sides 25 extend forward of the bottom of the bucket and have downwardly-inclined 5 points. These forward portions and the points coöperate to first cut side channels in the material to be removed. It will be obvious also that the bucket being carried by a single central chain to which it is pivotally secured and which extends on each 10 side of the chain, acts as a shield and prevents the materials from coming into contact with the sprocket and wheel as the bucket is gathering up its load. It will be seen that the bucket rests on the top of the 15 chain while carrying its load and that the bucket is so constructed that a change in the position of the elevator as a whole does not interfere with the latter safely and securely 20 carrying the coal or other material when loaded.

It will be obvious that when the bucket passes over the upper sprocket wheel that its load will be poured out of the open end 25 of the bucket. Consequently, for screening purposes I have arranged a screen 29 on which the material falls from the bucket. The screen 29 is carried by a frame 30 which is pivoted on a rod 31 which extends 30 between the arms 10. My purpose for making the screen adjustable is that it may be changed to handle material which present different conditions as to moisture or shape. Intermediate the ends of the frame 30 I 35 provide a gate 31' which is adapted to prevent the material from passing down the screen when so desired.

At the lower end of the frame 30 I provide a second gate such as 38 for convenience in bagging the material if so desired.

As shown in Fig. 1, the platform 2 is cut away under the screen 29 so that the fine

and undesirable material may fall onto the ground. If desired, however, this may be caught in any convenient manner.

45

It will be understood that the screen 29 is not permanently fixed to the frame 30 but may be changed so as to have a different meshed screen for handling different sizes of material.

50

Having thus described my invention, what I claim is:

1. In a screening apparatus, a bucket having an elongated chute portion adapted to rest on an elevator chain and a cutting plate 55 adapted to force its way into the material to be elevated and forming a pocket for the retention of the same, said bucket further having sides projecting forwardly of the cutting plate and provided with downwardly turned points, and attaching lugs on said bucket adapted to secure the bucket to a chain.

2. In a screening apparatus, a bucket having an elongated chute portion adapted to 65 rest on an elevator chain and a cutting plate adapted to force its weight into the material to be elevated and forming a pocket for the retention of the same, said bucket further having sides projecting forwardly of the 70 cutting plate and provided with downwardly turned points, and attaching lugs on said bucket adapted to secure the bucket to a chain, said lugs being arranged adjacent the forward end of the chute portion and 75 remote from the said points.

In testimony whereof, I have signed in the presence of the two undersigned witnesses:

ALBERT H. REYNOLDS.

Witnesses:

P. J. EDMUND, S.
E. A. BEDFORD.
